NECKTIE

Filed June 23, 1925

UNITED STATES PATENT OFFICE.

SIGMUND S. LOEB, OF BROOKLINE, MASSACHUSETTS.

NECKTIE.

Application filed June 23, 1925. Serial No. 39,015.

This invention relates to neckties more particularly of the four-in-hand type and has for its object to improve the appearance and wearing qualities of ties made from the 5 thinner and therefore inexpensive grades of silk. As heretofore commonly made ties of this thinner material have been provided with a relatively thick lining cut to the shape of the tie but shorter and about which the 10 silk has been folded and fixed. Sometimes this lining has been reinforced with a narrow strip positioned centrally of the width of the lining. This relatively heavy lining soon shows creases so that the appearance 15 of the tie is impaired after a short period of use. Because of this creasing tendency of the relatively thick lining, relatively thin lining material has been used but this when used with the thinner silks causes the tie to 20 have too little body to look well when tied.

According to the present invention that portion at least of the tie in which the knot is formed contains a lining composed of superposed plies of relatively thin lining 25 material, preferably of cotton or wool, each cut to full lining width and preferably cut bias to render that end of the tie elastic. Thus sufficient body is given to the tie without the creasing tendency of the heavier material. These plies or laminations are 30 preferably unattached over their major portions so that they are free to move relatively over each other. The creasing effects are thus individual to the several plies and do not 35 tend to become localized through the full thickness of the lining and consequently they do not become readily apparent.

It is also desirable that that portion of 40 the tie which passes around the collar should be so made as to slip readily around the collar and particularly when used in connection with a folded collar that it should be relatively thin and inelastic. The non-tying end of the tie should also be inelastic so that 45 it may be drawn upon to position the tie about the collar and to bring up the knotted portion of the tie thereagainst. The lining for the neckband portion of the tie and the 50 non-tying end is therefore preferably formed of a single layer of relatively thin lining material or fabric cut with the goods either longitudinally or laterally.

For a more complete understanding of 55 this invention reference may be had to the accompanying drawings in which—

Figure 1 is a rear elevation of a tie constructed according to this invention.

Figure 2 shows in perspective the lining pieces for the several portions of the tie detached.

Figures 3, 4 and 5 are detail sections on lines 3—3, 4—4 and 5—5, respectively, of Figure 1.

Referring to these drawings it will be seen that the lining for the tie comprises 60 superposed plies, preferably two, of fabric or other suitable lining material, as at 10, which extend from one end of the neckband portion as at 11 toward the free end of the tie to the point 12 as shown in Figure 1 and flare outwardly so as to substantially fill the covering material 14 between the points 11 and 12, the covering material being wrapped therearound and preferably attached to the superposed lining portions 10 on its rear face by means of the bar stitching 15 as shown best in Figures 1 and 5.

These lining sections 10 are preferably cut bias of the fabric so that they are elastic and are preferably of wool since this has 65 little creasing tendency. The remaining portion of the tie is lined as by means of a lining section 16 which is fixed to the sections 10 by the stitching at 11 and extends throughout the neckband portion of the tie 70 from the point 11 to the point 20 and toward the free end of the non-tying portion of the tie to the point 21. This lining section may be fixed in position through the covering material at the neckband portion by the 75 longitudinal lines of stitching 22 passing through both sides of the covering material and the lining strip. Adjacent to its opposite end this lining section 16 is fixed to the rear folded portion of the covering material 80 by means of the baring stitches 25. The neckband portion and the non-tying end are therefore lined with a comparatively thin material which is relatively non-stretchable 85 so that the tie may slip readily about the collar, and tension imparted to the non-tying end will serve to slide the tie about the collar, while the tying end has a lining of the full width thereof composed of superposed plies of thin elastic material which 90 gives the desired body to the tying portion of the tie and causes it to lie smooth when tied.

An important part of my invention consists of the discovery of the beneficial effect 110

upon the appearance and durability of the four-in-hand tie resulting from the use of a lining composed of a plurality, preferably two, of layers of thin cotton or woolen material. Upon the efficiency of the large end which forms the knot and also the exposed part of the tie when made up, mainly depends the merit and value of the tie as a whole.

10 The essential feature is the employment of two layers of relatively thin wool or cotton material in the large end unattached over their major portions to each other or to the silk cover.

15 By relatively thin material is understood a fabric substantially lighter than the single thickness of lining in general and common use.

This freedom of movement of the layers 20 of the lining and of the silk upon each other minimizes the tendency of deep and permanent wrinkles being formed in the long end of the silk, and thereby destroying the fresh appearance of the tie. Such deep wrinkles

25 or creases are caused when the entire lining and silk of the tie are creased several times in the same place or spot, as they will be when they are closely bound together. By reason of leaving the layers of the lining and

30 the cover of the tie practically free to move, their relations to each other change at different times so that the wrinkles made in the two layers of lining and of the silk at a given tying will not often meet at a later

35 tying and thereby not only prevent the making of deep wrinkles or creases, but by reason of the materials slipping upon each

other, a smooth surface of one presented to a wrinkle upon another tends to flatten out a wrinkle or crease caused by previous tying. 40

The layers of the lining and silk are free to slide upon each other slightly in all directions sufficiently to change the relations of their surfaces and present slightly different points of contact to each other on different 45 typings.

I have found in practice that a four-in-hand tie made in accordance with my invention will, in the hands of the ordinary user, be as free from wrinkles and present 50 as fresh an appearance after a dozen to fifteen typings as the tie with the usual single thickness of lining after a second or third tying, and when used with care it will be in good condition after many more typings. 55

Having thus described an embodiment of this invention, it should be evident to those skilled in the art that various changes and modifications might be made therein without departing from its spirit or scope as defined by the appended claims. 60

I claim:

1. A necktie having its tying end provided with a lining composed of a plurality of layers detached from each other substantially throughout their entire length. 65

2. A necktie having its tying end provided with a lining composed of a plurality of layers detached from each other and from the cover of said lining substantially 70 throughout their entire length.

In testimony whereof I have affixed my signature.

SIGMUND S. LOEB.
